(57) **CLAIM**

The ornamental design for a step light, as shown and described.

DESCRIPTION

FIG. 1 is a perspective view of a step light illustrating an example environment of the step light;

FIG. 2 is a perspective view of the step light;

FIG. 3 is a front view of the step light;

FIG. 4 is a left side of the step light;

FIG. 5 is a right side view of the step light;

FIG. 6 is a back view of the step light;

FIG. 7 is a top view of the step light; and,

FIG. 8 is a bottom view of the step light.

The broken lines in the figures are for illustrative purposes only and form no part of the claimed design.
